No. 14,618

FEB 5, 1884

8998

8998

UNITED STATES PATENT OFFICE.

CATHERINE O'HARA, OF NEW YORK, N. Y., ASSIGNOR TO THE BUTTERICK PUBLISHING COMPANY, (LIMITED,) OF SAME PLACE.

DESIGN FOR A CHILD'S COAT.

SPECIFICATION forming part of Design No. 14,618, dated February 5, 1884.

Application filed December 26, 1883. Term of patent 24 years.

To all whom it may concern:

Be it known that I, CATHERINE O'HARA, of the city, county, and State of New York, have invented and produced a new and original Design for a Pattern of a Child's Coat, (numbered 8,998;) and I do hereby declare that the engraved prints accompanying this specification convey to any one accustomed to using paper patterns a clear understanding of how to a garment made up by the pattern will appear.

The design shows loose fronts buttoned all the way down, a half-fitted back displaying

the lower parts of its side-back gores falling in tabs over plaited extensions of the center backs, coat-sleeves, and a rolling collar with square corners.

What I claim as my invention, and desire to secure by Letters Patent, is—

The design for a child's coat, as shown in the engraved prints accompanying this specification.

CATHERINE O'HARA.
